UNITED STATES PATENT OFFICE.

JOHN W. KINCAID, OF COVINGTON, KENTUCKY, ASSIGNOR OF ONE-THIRD
TO CHARLES A. KINCAID, OF COVINGTON, VIRGINIA.

MECHANICAL STOKER.

SPECIFICATION forming part of Letters Patent No. 714,712, dated December 2, 1902.

Application filed March 23, 1899. Serial No. 710,168. (No model.)

To all whom it may concern:

Be it known that I, JOHN W. KINCAID, a citizen of the United States, and a resident of Covington, in the county of Kenton and State of Kentucky, have invented certain new and useful Improvements in Mechanical Stokers, of which the following is a specification.

The object of my invention is a mechanical stoker especially adapted to be fitted to the furnaces of locomotives now in use in which the coal is fed at short intervals to the fire in small and well-spread quantities, whereby fuel is economized and no smoke is formed, which can be regulated readily to feed much or little, according to the amount of steam required, and by the use of which the firebox sheets and flues are protected from rapid changes of temperature, due to the inrushing of the outside air.

Referring to the drawings, in which like parts are indicated by similar reference-letters wherever they occur throughout the various views, Figure 1 is a plan view of a mechanical stoker embodying my invention attached to the door of a furnace, the door and the coal-hopper being shown in horizontal section upon line *y y* of Fig. 2. Fig. 2 is a view in side elevation of the same, one side of the incasing trough being broken away to expose the bottom of the hopper, the plunger, and the cylinder of the main engine. Fig. 3 is a transverse sectional view of the same, taken upon line *x x*, Fig. 2, looking toward the right. Fig. 4 is a detail sectional plan view, upon an enlarged scale, of the valve and the valve-case of the main engine, taken upon line *z z* of Figs. 2 and 5. Fig. 5 is a vertical sectional view of the same, taken upon line *v v*, Fig. 4. Fig. 6 is a detail plan view of the seat of the valve shown in Figs. 4 and 5. Fig. 7 is a similar view of the valve, the channel leading from the exhaust-port to the exhaust being shown in dotted line.

Referring to the parts, the bottom of the coal-hopper *A* has an opening *a* at the forward end through which coal fed forward by the spiral conveyer *C*, whose shaft *c* is journaled in the ends *a' and a''* of the hopper, passes to rest upon the apron *e*, which is attached at its forward end to the plunger *e'* and slides in ways between the hopper and

the cylinder *E* of the main engine until the plunger *e'* has been retracted, as shown in dotted lines, Fig. 2, when the coal drops down into the trough *D*, the rear half of which is secured by rivets *d* to the sides of the hopper *A* and the forward end of which passes through an opening in the furnace-door *F* above grate-bars *F'*. The plunger *e'* on its forward stroke throws the coal through the door *F*, opened, as shown in Figs. 1 and 2, into the furnace. Centrally secured to the furnace-door *F* at the end of the trough *D* is a deflector *F'*, in the shape of a half-cone, for spreading the coal. The plunger *e'* is actuated by the piston-rod *e''*, which extends through the head of the cylinder *E* of the main engine, which is run by steam from the boiler admitted to its valve-case *e''* through the pipe *e''*.

The valve-seat has two steam-ports *e''* and *e''* and two exhaust-ports *e''* and *e''*. While steam is being admitted through port *e''*, which communicates with the rear of the cylinder *E* through pipe *e''*, to advance the plunger *e'*, the steam in the forward end of the cylinder is exhausting through the port *e''* by the branch pipe *e''*, and while steam is being admitted by the port *e''* to the forward end of the cylinder through pipe *e''* to retract the plunger the rear end of the cylinder is exhausting through the port *e''* through the branch pipe *e''*.

That the coal may be well spread over the fire the forward stroke of the plunger is made to vary in rapidity from a stroke which would deposit the coal in front of the furnace-door to one that would throw it to the back of the furnace by varying each time the amount of steam admitted to the rear of the cylinder. To accomplish this, the following construction is used:

The valve *e''* has two ports *e''* and *e''*, the former to open the port *e''* and the latter the port *e''*. Mounted on the valve so as to turn around the valve-stem *e''* is a cam *e''*, secured to which is a ratchet-wheel *e''*, which is engaged by a spring-pressed pawl *e''*, which is mounted on the valve *e''*, so that when the valve is rotated in one direction the pawl rotates the cam, and when the valve is rotated in an opposite direction the cam is kept from rotating back with it by a spring-pressed pawl

e^{20} , attached to the interior wall of the valve-case e^3 .

The size of the port e^6 is unchanged, so that the return stroke of the plunger does not vary.

5 The rate at which the main engine runs may be regulated by the globe-valves e^{21} .

The spiral conveyer C is run by secondary engines, whose cylinders G and G' are either secured upon each side of the cylinder E by 10 braces g^1 or cast integral with said cylinder. To the steam-chests g^2 and g^3 of these cylinders steam is supplied from the valve-case e^3 — to the former through the pipe g^4 and to the latter through the branch pipe g^5 . The rate at 15 which these engines work may be regulated by globe-valves g^6 and g^7 . The conveyer-shaft c extends backward through the end a^2 of the hopper and terminates in a cog-wheel c' , which meshes with a worm c^2 upon the shaft c^3 , which 20 is journaled in standards e^{22} and e^{23} , secured to the rearwardly-extending flange e^{24} , which is secured to or formed integral with the top of the cylinder E. The shaft c^3 terminates in crank-heads c^4 and c^5 , coupled to the cross- 25 heads g^8 and g^9 by connecting-rods g^{10} and g^{11} . The valve-stems g^{12} and g^{13} , extending from the ends of steam-chests g^2 and g^3 , are reciprocated by shaft c^3 by means of sets of levers g^{14} and g^{15} , connected to eccentrics upon the 30 shaft by rods c^6 and c^7 and straps c^8 and c^9 . The steam from the exhaust-pipes m , m' , and m^2 is conveyed by the pipe M underneath the trough D against the deflector F' to keep it swept clean.

35 The valve-stem e^{16} terminates in an arm e^{25} , which is reciprocated by a rod H, which is supported in bracket-arms h^1 h^2 , secured to the trough D, and h^3 , secured to the sides of the cylinder G. The rod H is reciprocated 40 by an eccentric and strap c^{10} on the conveyer-shaft c by means of a lever h^4 , pivoted upon a post e^{26} , supported upon the flange e^{24} , a link h^5 , a link h^6 , and a rod c^{11} , which is secured to strap c^{10} and works back and forth 45 in a perforation in the standard e^{27} , supported by flange e^{24} .

When the plunger e' carries forward a charge of coal, the rod H, also on its forward stroke, bears against the angle-arm f, journaled upon the rod f' upon the outside of the trough D and passing through a curved slot in the side of the trough to bear against the small door f^2 , hung within the trough and swinging upon the rod f' , which passes 50 through the sides of the trough and is journaled in lugs f^3 and f^4 upon the furnace-door F, above whose opening, through which the trough D enters, is a second opening f^5 , through 55 which the fire may be stirred, which is closed by a door f^6 , swinging in lugs f^7 , secured to the door F. The small door f^2 is closed by a spring f^8 .

I have described my invention in substantially the same form in which I have made 65 and tested it; but it is obvious that many changes might be made in the specific de-

tails shown without departing from the spirit or scope of my invention.

What I claim is—

1. In a mechanical stoker the combination 70 of a piston-cylinder, a piston within the cylinder, means for admitting steam to and exhausting it from the cylinder to reciprocate the piston therein, a furnace, a trough leading from the cylinder into the furnace above the fire, a plunger within the trough, a rod connecting the piston and the plunger to communicate the acceleration of the piston to the plunger and means for feeding fuel automatically into the trough in front of the 80 plunger when it is retracted, substantially as shown and described.

2. In a mechanical stoker the combination 85 of a piston-cylinder, a piston within the cylinder, means for admitting steam to and exhausting it from the cylinder to reciprocate the piston therein, a furnace, a trough leading from the cylinder into the furnace above the fire, a plunger within the trough, a rod connecting the piston and the plunger to communicate the acceleration of the piston to the plunger, a hopper above the cylinder leaving a way between it and the cylinder and having an opening in advance of the front end of the cylinder, means for feeding fuel to the 95 front end of the hopper, and an apron secured to the plunger and reciprocating in the way so that fuel falls in front of the plunger when it is retracted, substantially as shown and described.

3. In a mechanical stoker the combination 100 of a piston-cylinder, a piston within the cylinder, means for admitting steam to and exhausting it from the cylinder to reciprocate the piston therein, a furnace, a trough leading from the cylinder into the furnace above the fire, a deflector secured to the forward end of the trough to spread the fuel, a plunger within the trough, a rod connecting the piston and the plunger to communicate the 105 acceleration of the piston to the plunger, and means for feeding fuel automatically into the trough in front of the plunger when it is retracted, substantially as shown and described.

4. In a mechanical stoker the combination 110 of the reciprocating plunger, the engine for reciprocating the plunger to whose cylinder is secured a trough leading into the fire-box of a furnace, said trough in which the plunger works, the hopper above the cylinder, the 115 apron secured to the plunger and sliding in ways between the hopper and cylinder to cause the coal to drop in front of the retracted plunger and prevent its falling between the plunger and cylinder, and means for varying the speed of the forward stroke of the plunger to throw the coal to different parts of the furnace, substantially as shown and described.

5. The combination of the furnace-door 120 with an opening to admit a trough and lugs 125 upon each side of the opening, the trough, a

door swinging within the trough upon a rod passing through the trough and resting in said lugs, the plunger reciprocating in the trough, the engine to reciprocate the plunger, means for feeding the coal in front of the retracted plunger, and a reciprocating rod for opening the door in advance of the plunger, substantially as shown and described.

6. In a mechanical stoker the combination of the reciprocating plunger, the trough in which the plunger works, the engine for reciprocating the plunger, the valve-case of said engine with the valve-seat the oscillating valve and the cam for varying the size of the port of the seat for admitting steam to advance the plunger with varying speed and means for feeding fuel into the trough in front of the plunger when retracted, substantially as shown and described.
- 10 7. In a mechanical stoker a trough or channel leading into a furnace above the grate-bars, a plunger in the channel, a conveyer for feeding fuel in front of the plunger, an engine for reciprocating the plunger, a valve for controlling the admission and exhaust of steam to and from the engine, and means for connecting the conveyer and the valve whereby the amount of fuel fed to the plunger is kept in proportion to the rate at which the plunger is reciprocated, substantially as shown and described.
- 20 8. In a mechanical stoker the combination of a reciprocating plunger for throwing fuel into a furnace above the grate-bars, an en-

gine for reciprocating the plunger, means for varying the speeds of the forward strokes of the plunger and means for feeding fuel in front of the retracted plunger, substantially as shown and described.

9. In a mechanical stoker the combination of a trough leading into the fire-box of a furnace, a plunger reciprocating within the trough, a piston-cylinder whose piston actuates the plunger, a hopper above the cylinder, an apron secured to the plunger and sliding in ways between the cylinder and the hopper to allow fuel to drop from the hopper in front of the plunger when it is retracted and means for admitting steam to the cylinder to reciprocate its piston, substantially as shown and described.

10. In a mechanical stoker the combination of a trough leading into the fire-box of a furnace, a reciprocating plunger within the trough, an engine secured at one end of the trough for reciprocating the plunger, a hopper above the cylinder of the engine, an apron secured to the plunger and sliding in ways between the hopper and cylinder, a spiral conveyer rotating within the bottom of the hopper to feed fuel in front of the retracted plunger and means for rotating the conveyer, substantially as shown and described.
